(57) **CLAIM**

The ornamental design for a folding table, as shown and described.

DESCRIPTION

FIG. 1 is a perspective view of a folding table showing my new design;

FIG. 2 is a right-side view thereof;

FIG. 3 is a left-side view thereof;

FIG. 4 is a front view thereof;

FIG. 5 is a rear view thereof;

FIG. 6 is a top view thereof;

FIG. 7 is a bottom view thereof;

FIG. 8 is a bottom view of the folding table shown in a partially folded position; and,

FIG. 9 is a top view of the folding table shown in a completely folded position.

The broken lines in the drawings depict portions of the folding table that form no part of the claimed design.
